O. RIGTER.

CARPET.

No. 16,298.

Patented Sept. 29, 1885.

UNITED STATES PATENT OFFICE.

OSCAR RIGHITER, OF PHILADELPHIA, PENNSYLVANIA, ASSIGNOR TO DORNAN BROS. & CO., OF SAME PLACE.

DESIGN FOR A CARPET.

SPECIFICATION forming part of Design No. 16,298, dated September 29, 1885.

Application filed August 14, 1885. Term of patent 3½ years.

To all whom it may concern:

Be it known that I, OSCAR RIGHITER, of the city of Philadelphia, county of Philadelphia, State of Pennsylvania, have invented and produced a new and original Design for Carpets, of which the following is a specification.

The nature of my design is fully represented in the accompanying photographic illustration, to which reference is made.

I claim--

The design for carpets as herein shown and described.

OSCAR RIGHITER.

Witnesses:

T. BENTON DORNAN,
SAMUEL BOGGS.
